ARTIFICIAL DENTURE STRUCTURES

George E. Lester, Encino, and William Lester, Burbank, Calif.

Application May 2, 1955, Serial No. 505,484

10 Claims. (Cl. 32—2)

The present invention relates to artificial denture structures, and more particularly to the relieving of stress in prosthetic teeth.

An object of the invention is to provide an improved prosthetic tooth structure, such as a fixed bridge or a partial denture, which gives greater comfort to the person, restoring the function of the teeth which it replaces, is sanitary in use, and is not harmful to the gums and other tissues in the mouth.

Another object of the invention is to provide an artificial tooth structure in which the tooth is relieved of stress, the pressure on the person's gums being minimized considerably. The gums are relieved of shock by permitting the artificial teeth to yield slightly under load.

A further object of the invention is to provide an artificial tooth structure in which the tooth or teeth are allowed to yield slightly under load, thereby providing a stress breaker which relieves the adjacent normal or anchor teeth of some of the load and pressure. By virtue of the arrangement, the tendency of the anchor or abutment teeth to drift from normal position is minimized.

Yet another object of the invention is to provide a prosthetic tooth structure, in which the artificial tooth or teeth are allowed to move independently of one another.

Still a further object of the invention is to provide an improved stress breaker in denture work which can be used in full uppers and lowers.

This invention possesses many other advantages, and has other objects which may be made more clearly apparent from a consideration of several forms in which it may be embodied. Such forms are shown in the drawings accompanying and forming part of the present specification. These forms will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a section through an artificial denture embodying the invention;

Fig. 2 is a section taken along the line 2—2 on Fig. 1;

Fig. 3 is a section through another embodiment of the invention, disclosing a plurality of prosthetic teeth;

Fig. 4 is a view similar to Fig. 1 of still another form of the invention.

In a fixed bridge, or the like, the rigid securing of the abutment teeth to each other, or of the artificial tooth or teeth to the abutment teeth, provides interference with the individual movement of the teeth, which can result in serious and unfavorable tissue reaction, or fracture of the cusps of the teeth.

By virtue of the invention, each artificial tooth is yieldably mounted so as to have limited movement under restraint independently of an adjacent tooth, which may be another artificial tooth or an anchor tooth. The artificial teeth may move independently and individually of

the teeth adjacent thereto in a generally vertical direction, to minimize any bending action that would otherwise be imposed on the adjacent tooth or teeth. The restraint is provided by one or more springs, which will only yield when the bite load on the artificial teeth is quite pronounced, the resistance to movement of the artificial tooth increasing as the load thereon increases, in order to insure proper biting action of the artificial teeth against an opposed tooth or any substances therebetween.

Despite the ability of the artificial tooth to move independently of the adjacent teeth, food particles and other materials are prevented from passing into the artificial tooth structure, retaining it in a sanitary condition.

As disclosed in Figs. 1 and 2, an artificial tooth 10, which may be made of porcelain, plastic or metal, is mounted in a cylindrical cavity 11 provided in a denture base 12 made of a suitable material. The tooth 10 can move vertically a relatively slight distance against the force provided by a spring 13 which may be in the form of a coil or helical spring member preferably confined within a telescopic housing structure secured to the artificial tooth 10 and also to the denture base 12 itself. As specifically disclosed, the telescopic housing structure includes an outer housing 14 having a base 15 suitably secured, as by soldering, to an outer cylindrical housing portion 16 having an outwardly directed flange 17 at one end, this flange and the marginal portion of the base 15 being received within an internal peripheral groove 18 in the denture base circumscribing the cylindrical cavity 11, appropriately anchoring the outer housing 14 and its base 15 to the denture base 12, the base 15 of the housing resting upon the bottom 19 of the cylindrical cavity 11.

The outer cylindrical housing portion 16 engages the wall of the cylindrical cavity 11, terminating in an upper web 20 merging into an inner skirt 21 extending toward the housing base 15. The inner skirt 21 is spaced from the outer housing wall 16 to form a circumferentially continuous groove 22 opening in a direction toward the base 15.

Similarly, an inner housing 23 is secured to the artificial tooth 10, its inner cylindrical wall 24 extending upwardly into the lower portion of the tooth 10, there being an upper annular flange 25 soldered, or otherwise suitably secured, to the upper end of the inner cylindrical wall 24 and received within a companion cavity in the tooth, by virtue of which the tooth 10 and inner cylindrical wall 24 are rigidly anchored to each other. Extending across the inner end surface of the artificial tooth and in engagement therewith is a plate 26 appropriately secured to the inner cylindrical wall 24, as by being soldered thereto.

The lower portion of the inner cylindrical wall 24 terminates in a lower web 27 that merges into an upwardly extending skirt 28 fitting within the circumferential groove 22 of the outer housing 14. The skirt 28 of the inner housing and the inner cylindrical wall 24 are also spaced from each other to provide a circumferentially continuous groove 29 opening in a direction toward the artificial tooth 10 and adapted to slidably receive the skirt 21 of the outer housing member.

The housing structures 14, 23 are slidable vertically with respect to each other, being guided in such sliding movement by virtue of the relatively close sliding fit that the respective skirts 21, 28 have in the grooves 29, 22 provided in the other housing members.

The compressed helical spring 13 is disposed within the housing structure, one end of the spring bearing upon the base 15 of the outer housing and the other end of the spring bearing against the plate 26 secured to the inner housing structure and engaging the inner end surface of the artificial tooth 10. The spring 13 tends to force the

artificial tooth outwardly of the denture base 12, the extent of outward shifting being limited by engagement of the inner web 27 with the lower end of the skirt 21 of the outer housing 14. The application of the inward pressure on the artificial tooth of sufficient magnitude causes the spring 13 to compress, the tooth moving within the cylindrical cavity 11 formed in the denture base to the extent limited by collapse of the spring to its solid height, or by engagement of the lower web 27 with the base 15 of the outer housing. During such downward movement, the skirts 21, 23 are slideable along each other, as well as along the inner and outer walls of the housing structure, to limit the movement of the artificial tooth to a direction axially of the central common axis of the housing structure and the cylindrical cavity 11. During such movement of the tooth in the cavity, the outer surface 30 of the tooth 10 makes a relatively close sliding fit with the wall and the cylindrical cavity 11, to minimize the opportunity for food and other particles to enter the cavity 11.

When the pressure on the artificial tooth 10 is relieved or decreased, the spring 13 will urge the tooth outwardly of the denture base 12 toward its initial position.

The denture device described provides a completely enclosed housing structure for the spring 13, in view of the relatively close sliding fit between the inner and outer housing parts. Thus, the spring 13 and the housing structure 14, 23 can be prefabricated and preassembled and need only be cast into an artificial tooth 10 and into the denture base 12 to secure a complete denture structure in which the tooth is capable of independent movement with respect to the denture base. Thus, the tooth does not impose any bending or other loads on adjacent teeth, such as would be harmful to the tissues and which might cause fracture of adjoining tooth cusps.

The housing structure and spring may be made of stainless steel or other suitable material that will have no harmful effects on the person and which will possess an exceedingly long life.

In the form of invention disclosed in Fig. 3, the denture base 12a has a plurality of artificial teeth 10, 10a mounted therein. Each tooth may have the same spring-like or yieldable mounting in the denture base 12a, the latter, of course, fitting against the gum tissue. Each artificial tooth may move independently of the adjacent artificial tooth, to avoid a bending action on the denture base, or, if desired, the artificial teeth can be secured to one another, as by use of suitable soldering material 31. It is preferred, however, that the teeth 10, 10a be mounted for independent movement relative to the denture base 12a.

As disclosed in Fig. 3, one of the teeth 10a may move relative to the denture base 12a against the resistance offered by a different form of spring 13a. Instead of the helical spring 13 illustrated in Fig. 1, and on the left and right teeth 10 shown in Fig. 3, the spring 13a may take the form of a bowed type of leaf spring, in which the medial portion 32 of the spring bears against the base 15 of the outer housing, and in which the outer arms 33 of the spring bear against the plate 26 of the inner housing. Inasmuch as the range of movement of an artificial tooth under a load is relatively small, the spring 13a will never be collapsed fully, and will always be effective to yieldably support the artificial tooth 10a, allowing it to move inwardly of the denture base 12a under load, and returning it to its initial position when the load is removed.

The form of invention shown in Fig. 4 is essentially the same as the one disclosed in Fig. 1. However, a plurality of helical springs 13b is provided. Thus, the base 15b of the outer housing may have a plurality of centering pins 35 therein in alignment with opposed centering pins 36 projecting from the plate 26b. A helical compression spring 13b is disposed in the housing structure, each spring having one end bearing against

the base 15b and surrounding a centering pin 35, its other end bearing against the plate 26b and surrounding a centering pin 36 of the latter. In all general respects, however, the structure disclosed in Fig. 4 operates in the same manner as the structure disclosed in Fig. 1, except that it is possible to provide a much greater spring force with the plurality of smaller springs 13b shown in Fig. 4 than can be provided with the single spring 13 disclosed in Fig. 1.

It is, accordingly, evident that artificial denture structures have been provided which act as stress breakers, to relieve the adjacent artificial or natural teeth of stress, each tooth being allowed to move independently of adjacent teeth, but against a predetermined resistance afforded by the spring, or the like. The provision of the stress breaker arrangement minimizes the tendency for the anchor or abutment teeth to drift from their normal position, relieving the pressure on the person's gums, as well as the shock that would be imposed thereon in the event of a rigid mounting of the artificial teeth with respect to adjacent teeth in the person's mouth.

The inventors claim:

1. In prosthetic tooth structures: a denture base having a cavity therein; an artificial tooth movable in said cavity; a member in said cavity secured to said base; a mounting member in said cavity secured to said tooth; means acting between and engaging said members for yieldably urging said tooth in a direction outwardly of said cavity; and coengagable stop means on said members for limiting the extent of movement of said tooth in a direction outwardly of said cavity.

2. In prosthetic tooth structures: a denture base having a cavity therein; an artificial tooth movable in said cavity; a member in said cavity secured to said base; a mounting member in said cavity secured to said tooth; a spring acting between and engaging said members for yieldably urging said tooth in a direction outwardly of said cavity; and coengagable stop means on said members for limiting the extent of movement of said tooth in a direction outwardly of said cavity.

3. In prosthetic tooth structures: a denture base having a cavity therein; an artificial tooth movable in said cavity; a housing member in said cavity secured to said base; a housing member in said cavity secured to said tooth; a spring in said housing members for urging said tooth in a direction outwardly of said cavity; and coengagable means on said housing members for limiting the extent of movement of said tooth in a direction outwardly of said cavity.

4. In prosthetic tooth structures: a denture base having a cavity therein; an artificial tooth movable in said cavity; a housing member in said cavity secured to said base; a housing member in said cavity secured to said tooth; a helical compression spring in said housing members for urging said tooth in a direction outwardly of said cavity; and coengagable means on said housing members for limiting the extent of movement of said tooth in a direction outwardly of said cavity.

5. In prosthetic tooth structures: a denture base having a plurality of cavities therein; an artificial tooth movable in each of said cavities; a housing member in each of said cavities secured to said base; a housing member in each of said cavities secured to each tooth; a spring for each tooth in said housing members for urging said tooth in a direction outwardly of said cavity independently of movement of an adjoining tooth; and coengagable means on said housing members for each tooth for limiting the extent of movement of said tooth in a direction outwardly of said cavity.

6. In prosthetic tooth structures: a denture base having a cavity therein; an artificial tooth movable in said cavity; a housing member in said cavity secured to said base; a housing member in said cavity secured to said tooth; a leaf spring in said housing members for urging said tooth in a direction outwardly of said cavity; and coengagable

means on said housing members for limiting the extent of movement of said tooth in a direction outwardly of said cavity.

7. In prosthetic tooth structures: a denture base having a cavity therein; an artificial tooth movable in said cavity; a housing member in said cavity secured to said base; a housing member in said cavity secured to said tooth; a plurality of helical compression springs in said housing members for urging said tooth in a direction outwardly of said cavity; and coengagable means on said housing members for limiting the extent of movement of said tooth in a direction outwardly of said cavity.

8. In prosthetic tooth structures: a denture base having a cavity therein; an artificial tooth movable in said cavity; a first housing member in said cavity secured to said denture base, said member including a base portion bearing against the bottom of said cavity; a second housing member in said cavity secured to said tooth and telescopically related to said first housing member, said second member having a plate bearing against the upper end of said tooth; a spring in said housing members bearing against said base portion and plate for urging said tooth in a direction outwardly of said cavity; and coengagable means on said housing members for limiting the extent of movement of said tooth in a direction outwardly of said cavity.

9. In prosthetic tooth structures: a denture base having a cavity therein; an artificial tooth movable in said cavity; an outer, generally cylindrical housing member in said cavity secured to said denture base, said outer member including an outer wall portion and an inner skirt secured to and spaced from said wall portion to provide a first circumferential groove opening toward the bottom of said cavity; an inner, generally cylindrical housing member in said cavity secured to said tooth, said inner

30
35

member including an inner wall portion and an outer skirt secured to and spaced from said inner wall portion to provide a second circumferential groove opening toward said tooth; said inner skirt and outer skirt being telescopically movable in said second and first grooves, respectively; and spring means in said housing members for urging said tooth in a direction outwardly of said cavity.

10. In prosthetic tooth structures: a denture base having a cavity therein; an artificial tooth movable in said cavity; an outer, generally cylindrical housing member in said cavity secured to said denture base, said outer member including an outer wall portion and an inner skirt secured to and spaced from said wall portion to provide a first circumferential groove opening toward the bottom of said cavity; an inner, generally cylindrical housing member in said cavity secured to said tooth, said inner member including an inner wall portion and an outer skirt secured to and spaced from said inner wall portion to provide a second circumferential groove opening toward said tooth; said inner skirt and outer skirt being telescopically movable in said second and first grooves, respectively; said outer member including a base portion bearing against the bottom of said cavity; said inner member including a plate bearing against the inner end of said tooth; and spring means in said housing member bearing against said base portion and plate for urging said tooth in a direction outwardly of said cavity.
